BRUSH

Clarence G. Rowland, Newington Junction,
Conn., assignor to The Fuller Brush Company,
Hartford, Conn., a corporation of Connecti-
cut

Application January 16, 1935, Serial No. 2,073

5 Claims. (Cl. 15—205)

My invention relates to the class of articles above mentioned, and an object of my invention, among others, is to provide a means for economically forming the backs to receive the brush material and in which backs said material will be tightly held in a very efficient manner.

One form of a brush embodying my invention and in the construction and use of which the objects herein set out, as well as others, may be attained is illustrated in the accompanying drawing in which

Figure 1 is a plan view of my improved brush blank.

Figure 2 is a view in cross section through the same.

Figure 3 is a similar view showing a slightly modified form of construction.

Figure 4 is another similar view showing another modified form of construction.

Figures 5, 6 and 7 are detail views showing the final form of brushes embodying the blanks shown in Figs. 2, 3 and 4.

In the accompanying drawing the numeral 8 denotes a strip of metal having ribs 9 bordering the strip on opposite sides, leaving a space 10 which extends lengthwise of the strip and as shown in Fig. 1 of the drawing. This strip is folded lengthwise into a shape shown in Fig. 5 of the drawing, with the bristles 11 projecting from within the backs through the slots 12 created by the bending or folding operation. The strip 8 may be of indefinite length and the folding or bending operation may be accomplished by means of a machine, which machine also inserts the bristles and folds them so that at the end of the operation said bristles are securely bound and pinched between the lips 13, the ribs 9 providing a restricted pressure neck lying on opposite sides of the mouth of the groove and between which the bristles are securely held in place. These lips are rounded as at 14 so that the bristles, as they are flexed in use, will have a long bend over the rounded corners and therefore be prevented from breaking off at this point.

If desired a holding rod 15 may be inserted in the folds of the bristles within the backs, this rod serving an additional means for retaining the bristles in place.

In that form of structure shown in Figs. 3 and 6 the essential characteristics are substantially the same as just described, the ribs, however, being composed of a folded edge 16 at opposite borders of the backs 17, this piece when folded functioning in practically the same manner to hold the bristles as in the device shown in Figs. 1, 2 and 5.

In the structure shown in Figs. 4 and 7 the

ribs 18 are beveled on opposite sides, as shown in Fig. 4, so that when the strip 19 is bent to the final shape shown in Fig. 7 with the bristles secured therein the latter will pass through the narrow throat 20 outside of which there is a 5 mouth with sloping walls 21 to receive the bristles and thereby prevent sharp bending and consequent breaking thereof.

In accordance with the provisions of the patent statutes I have described the principles of 10 operation of my invention, together with the device which I now consider to represent the best embodiment thereof; but I desire to have it understood that the device shown is only illustrative and that the invention may be carried out 15 by other means and applied to uses other than those above set out within the scope of the appended claims.

I claim:

1. A brush back comprising a strip of material 20 having a lengthwise groove and having a continuously thickened edge extending lengthwise thereof to provide a restricted pressure neck to retain the bristles in place.

2. A brush back comprising a strip of material 25 of substantially uniform thickness and having a lengthwise groove having its edge border shaped to create continuously thickened edges extending lengthwise thereof to provide a restricted pressure neck to retain the bristles in place.

3. A brush comprising a back formed from a strip of material of substantially uniform thickness thickened continuously along its opposite edges and having a groove extending lengthwise to provide a restricted pressure neck, and bristles 35 secured within said back and projecting with their free ends outwardly through said pressure neck.

4. A brush comprising a back formed from a strip of material of substantially uniform thickness formed lengthwise at opposite edges to provide continuously thickened borders extending lengthwise thereof, said strip having a groove extending lengthwise and said borders comprising a restricted pressure neck, and bristles 40 secured within said back and projecting with their free ends outwardly through said pressure neck.

5. A brush comprising a back formed from a strip of material of substantially uniform thickness and having ridges on opposite sides of its 50 lengthwise center extending continuously therealong and beveled in opposite directions, said strip having a groove extending substantially along its lengthwise center to create a restricted pressure neck formed by said ridges, and bristles 55 secured within said back and projecting with their free ends outwardly through said pressure neck.

CLARENCE G. ROWLAND.
